[57] CLAIM

The ornamental design for the chipcard, as shown and described.

DESCRIPTION

FIG. 1 is a top front and side perspective view of a chipcard showing my new design;

FIG. 2 is a bottom perspective view thereof;

FIG. 3 is a top front and side perspective view of a second embodiment thereof; and,

FIG. 4 is a bottom perspective view thereof.

The undisclosed rear and opposite side elevational views are identical to those sides shown in the views and the beveled corner is flat and unornamented.
